(57) **CLAIM**

The ornamental design for a control panel for freezer, as shown and described.

DESCRIPTION

FIG. 1 is a perspective view of a control panel for freezer according to the first embodiment, showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a cross-sectional end view thereof showing only a cut surface of a cut part 8-8 in FIG. 2 with the internal structure being omitted;

FIG. 9 is a cross-sectional end view thereof showing only a cut surface of a cut part 9-9 in FIG. 2 with the internal structure being omitted;

FIG. 10 is a cross-sectional end view thereof showing only a cut surface of a cut part 10-10 in FIG. 2 with the internal structure being omitted;

FIG. 11 is an enlarged cross-sectional end view showing a part thereof delineated by area 11 in FIG. 8;

FIG. 12 is an enlarged cross-sectional end view showing a part thereof delineated by area 12 in FIG. 9;

FIG. 13 is an enlarged cross-sectional end view showing a part thereof delineated by area 13 in FIG. 10;

FIG. 14 is an enlarged view showing a part thereof delineated by area 14 in FIG. 1;

FIG. 15 is an enlarged view showing a part thereof delineated by area 15 in FIG. 2;

(Continued)

FIG. 16 is a perspective view of the front, top and right side of a control panel for freezer according to the second embodiment, showing our new design;

FIG. 17 is a perspective view of the rear, top and right side thereof;

FIG. 18 is a front view thereof;

FIG. 19 is a rear view thereof;

FIG. 20 is a left side view thereof;

FIG. 21 is a right side view thereof;

FIG. 22 is a top view thereof;

FIG. 23 is a bottom view thereof;

FIG. 24 is a cross-sectional end view thereof showing only a cut surface of a cut part 24-24 in FIG. 18 with the internal structure being omitted;

FIG. 25 is a cross-sectional end view thereof showing only a cut surface of a cut part 25-25 in FIG. 18 with the internal structure being omitted; and,

FIG. 26 is a cross-sectional end view thereof showing only a cut surface of a cut part 26-26 in FIG. 18 with the internal structure being omitted.

The broken lines shown represent portions of a control panel for freezer that form no part of the claimed design.

The dot-dashed lines represent boundaries of the enlarged parts that form no part of the claimed design.
